CLAIM

The ornamental design for a component for a single draw container insert having two metered flow outlets, as shown and described.

DESCRIPTION

FIG. 1 is an upper perspective view of a component for a single draw container insert having two metered flow outlets;

FIG. 2 is a top view thereof;

FIG. 3 is a first side view thereof;

FIG. 4 is a second side view thereof;

FIG. 5 is a third side view thereof;

FIG. 6 is a fourth side view thereof; and,

FIG. 7 is a bottom view thereof.

The broken lines and unshaded areas adjacent to the broken lines depict portions of the component for a single draw container insert having two metered flow outlets that form no part of the claimed design.
